US00D995531S

(12) **United States Design Patent** (10) **Patent No.:** **US D995,531 S**
Cai (45) **Date of Patent:** **** Aug. 15, 2023**

(54) **HUB**

(71) Applicant: **SHENZHEN DEONE INNOVATION TECHNOLOGY CO., LTD**, Shenzhen (CN)

(72) Inventor: **Xueliang Cai**, Shenzhen (CN)

(73) Assignee: **SHENZHEN DEONE INNOVATION TECHNOLOGY CO., LTD**, Shenzhen (CN)

(**) Term: **15 Years**

(21) Appl. No.: **29/857,844**

(22) Filed: **Oct. 26, 2022**

Related U.S. Application Data

(62) Division of application No. 29/847,674, filed on Jul. 27, 2022, now Pat. No. Des. 982,013.

(30) **Foreign Application Priority Data**

Jul. 14, 2022 (CN) 202230447444.5

(57) **CLAIM**

The ornamental design for a hub, as shown and described.

DESCRIPTION

FIG. 1 is a perspective view of a hub showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the hub where the hub is in a configuration of use.

The broken lines in the drawings depict portions of the hub that form no part of the claimed design.

1 Claim, 9 Drawing Sheets
